(57) **CLAIM**

The ornamental design for a bottle, as shown and described.

DESCRIPTION

FIG. 1 is a side perspective view of a first embodiment of a bottle, embodying our new design;

FIG. 2 is a left side elevation view of the embodiment of FIG. 1;

FIG. 3 is a right side elevation view of the embodiment of FIG. 1;

FIG. 4 is a rear elevation view of the embodiment of FIG. 1;

FIG. 5 is a front elevation view of the embodiment of FIG. 1;

FIG. 6 is a top plan view of the embodiment of FIG. 1;

FIG. 7 is a bottom plan view of the embodiment of FIG. 1;

FIG. 8 is a side perspective view of a second embodiment thereof, shown with a cap; and,

FIG. 9 is an alternate rear elevation view of the embodiments of FIGS. 1 and 8.

The broken lines elements in FIG. 7 are for illustrative purpose only and form no part of the claimed design.
